(57) **CLAIM**

We claim the ornamental design for a shelving post collar, as shown and described.

DESCRIPTION

FIG. 1 is a perspective front top left side of the shelving post collar.

FIG. 2 is a front elevation view thereof.

FIG. 3 is a left side elevation view thereof.

FIG. 4 is a top plan view thereof.

FIG. 5 is a right side elevation view thereof.

FIG. 6 is a back elevation view thereof.

FIG. 7 is a bottom plan view thereof.

FIG. 8 is a perspective top right side back view thereof; and,

FIG. 9 is a perspective view of the shelving post collar in use. The broken lines in the drawing depict environmental subject matter only and form no part of the claimed design.
